[57] CLAIM

The ornamental design for a ring, as shown and described.

DESCRIPTION

FIG. 1 is a top plan view of a ring showing my new design;
FIG. 2 is a right-side elevational view thereof, the left side being a mirror image thereof;
FIG. 3 is a front elevational view thereof, the rear side being a mirror image thereof;
FIG. 4 is a bottom plan view thereof;
FIG. 5 is a top plan view of a ring showing an alternate embodiment of my new design;
FIG. 6 is a right-side elevational view of an alternate embodiment of my new design, the left side being a mirror image thereof;
FIG. 7 is a front elevational view of an alternate embodiment of my new design, the rear side being a mirror image thereof;
FIG. 8 is a bottom plan view of an alternate embodiment of my new design;
FIG. 9 is a top plan view of a ring showing a second alternate embodiment of my new design;
FIG. 10 is a right-side elevational view of the second alternate embodiment of my new design, the left side being a mirror image thereof;
FIG. 11 is a front elevational view of the second alternate embodiment of my new design, the rear side being a mirror image thereof; and
FIG. 12 is a bottom plan view of the second alternate embodiment of my new design.
